UNITED STATES PATENT OFFICE.

THERON R. PALMER, OF ERIE, PENNSYLVANIA.

DESIGN FOR A HANDLE-GRIP.

52,489.

Specification for Design.

Patented Sept. 24, 1918.

Application filed April 23, 1917. Serial No. 164,066. Term of patent 7 years.

To all whom it may concern:

Be it known that I, THERON R. PALMER, a citizen of the United States, residing at Erie, in the county of Erie and State of Pennsylvania, have invented a certain new, original, and ornamental Design for Handle-Grips, of which the following is a specification, reference being had to the accompanying drawings, forming part thereof, in which—

Fig. 2, shows a transverse section thereof.

I claim:

The ornamental design for a handle-grip as shown.

In testimony whereof I affix my signature.

THERON R. PALMER.
